Specification of Letters Patent. Patented Aug. 22, 1922.

Application filed February 25, 1922. Serial No. 539,088.

To all whom it may concern:

Be it known that I, OSWALD SCHLAUPITZ, a citizen of the United States, and a resident of the city of Canton, in the county of 5 Stark and State of Ohio, have invented a new and useful Improvement in Presses, of which the following is a specification.

My invention relates to presses in which an article is mounted on the bed of the press 10 and is acted on by a die that is secured to the end of a plunger. The invention has for its principal objects to provide means for easy adjustment of said press for working on articles of different sizes and to accommodate articles of slightly varying sizes 15 without the necessity for adjusting the press. The invention consists principally in a yieldable seat for the work and in means for varying the pressure at which said seat 20 will yield to the force of the plunger. The invention further consists in the parts and combinations of parts hereinafter described and claimed.

In the drawing, which forms part of this 25 specification and wherein like reference numerals indicate like parts wherever they occur,

Fig. 1 is a side elevation of a press embodying my invention, certain parts being 30 shown in section;

Fig. 2 is a part end elevation and part sectional view along the line 2--2 in Fig. 1; and

Fig. 3 is a sectional view along the line 35 3--3 in Fig. 1.

It is common practice to stamp marks of various kinds in the end of a roller bearing cup or the like, by means of a die 1 that is secured at the end of the reciprocating 40 plunger 2 of a suitable press that comprises a base or pedestal 3 and a bed 4. Obviously, if articles of different heights are to be marked in one press, numerous adjustments 45 are necessary. Heretofore such adjustments have required changing the stroke of the plunger or raising or lowering the bed of the press, which operations are rather difficult and do not permit of nice adjustment 50 of the plunger stroke. A further disadvantage of ordinary presses is that the cup or the like is seated on rigid bed and is liable to be damaged by the sudden impact of the plunger.

According to the present invention, the 55 cup is placed on a yieldable or floating seat

10 that is mounted in the bed 4 of the press. Preferably said seat 10 is provided with a shank portion 11 that fits in a tubular member 12 that is mounted in a suitable hole in the bed of the press. The tubular member 60 12 is provided with a circumferential rib or flange 13 whereby it is secured to the underside of the bed as by bolts 14. The lower end of the shank 11 of the floating seat 10 rests on the short arm of a lever 15 which 65 is pivotally secured to the projecting lower end of the tubular member 12. Said tubular member is provided with a suitable opening into which the end of lever 15 extends. The end of said lever 15 is formed 70 into a suitable seat 16 to receive the lower end of the shank 11 of the floating seat. The long arm of the lever 15 is provided with a suitable knife edge 17 at the end which contacts with the lower edge of a 75 second lever 18 that is pivotally secured to a suitable projection 19 on the underside of the bed 4 of the press and which extends in substantially the same plane as the first lever 15. The second lever 18 is provided 80 with a plurality of notches 20 along its upper edge. In one of said notches rests a shackle 21 whose lower end is provided with a downwardly extending rod 22 having a threaded end portion on which is mounted 85 one end of a turnbuckle 23. The lower end of said turnbuckle 23 is secured to the threaded upper end of a rod 24 to whose lower end is secured one end of a coil spring 25. The other end of said coil spring is 90 suitably secured to the base 3 of the press.

The operation of the device is as follows. A cup or other article 26 to be marked is placed on the yieldable seat 10 in position to be struck by the die 1 on the downward 95 stroke of the plunger 2. When the cup is struck by the die, the yieldable seat 10 will yield to an extent permitted by the spring 25 which, operating through the levers 15 and 19 tends to hold said seat in its uppermost position. The upward movement of the seat 10 is limited as the arm of the lever 15 strikes the wall of the tubular member 12. The parts are adjusted so that the seat 10 will cease to yield before the end of 105 the downward stroke of the plunger 2, and thus the die will imprint its mark in the end of the cup 26 or the like. If it is desired to imprint a deeper mark in the end 110 of the cup or if a smaller cup is to be

stamped, the point at which the spring overcomes the force of the plunger may be changed by turning the turnbuckle 23 or by moving the shackle to a different notch of the second lever. In the drawing, said shackle is shown in the outmost notch, indicating that the press is being used on a very small article.

The hereinbefore described press permits easy and accurate adjustment of the seat on which the article to be stamped is mounted. It provides a yielding seat for said article, thus minimizing the danger of damage during the stamping operation. A given press may be used for stamping articles of various sizes. If an article being marked is slightly off size, the fact that it is yieldably mounted will avoid both the danger of the article being broken (if it is oversize) or of no impression being made (if the article is undersize).

I have shown the invention embodied in a hand fed press, but obviously my invention relates particularly to yieldable means for supporting the article in the press, and may be used in presses of entirely different kinds from that shown in the drawings. Numerous changes may be made without departing from my invention and I do not wish to be limited to the precise construction shown.

What I claim is:

1. In a press of the kind set forth, a seat for the work, a lever that has one arm formed into a support for said seat, a second lever disposed above the outer end of said first lever and engaged thereby means comprising a spring for depressing the end of said second lever, thereby holding said seat in its uppermost position, and means for adjusting the pull of said spring on said lever.

2. In a press of the kind set forth, a yieldable seat for the work, said seat having a shank portion, a lever whose short arm is formed into a support for the end of the shank portion of said yieldable seat, a second lever disposed above the outer end of said first lever and engaged thereby and means comprising a spring for depressing the end of said second lever.

3. In a press of the kind set forth, a yieldable seat for the work, said seat having a shank portion, a lever whose short arm is

formed into a support for the end of the shank portion of said yieldable seat, a second lever disposed above the outer end of said first lever and engaged thereby, and means tending to depress the end of said second lever.

4. In a press of the kind set forth, a yieldable seat for the work, said seat having a shank portion, a lever whose short arm is formed into a support for the end of the shank portion of said yieldable seat, a second lever disposed above the outer end of said first lever and engaged thereby and means for depressing the end of said second lever, said means comprising a shackle engaging said lever, a spring secured to the base of the press, rods secured to and extending towards each other from said shackle and spring, respectively, and a turnbuckle connecting said rods.

5. In a press of the kind set forth, a yieldable seat for the work, said seat having a shank portion, a lever whose short arm is formed into a support for the end of the shank portion of said yieldable seat, a second lever disposed above the outer end of said first lever and engaged thereby and means for depressing the end of said second lever, said means comprising a shackle engaging said lever, a spring secured to the base of the press, rods secured to and extending towards each other from said shackle and spring, respectively, and a turnbuckle connecting said rods, said lever having a plurality of notches in which said shackle may be disposed.

6. In a press of the kind set forth, a yieldable seat for the work, said seat having a shank portion, a lever whose short arm is formed into a support for the end of the shank portion of said yieldable seat, a second lever disposed above the outer end of said first lever and engaged thereby, and means tending to depress the end of said second lever, said means comprising a shackle engaging said lever, a spring secured to the base of the press and means connecting said shackle and spring.

Signed this 21st day of February, 1922, at Canton, Ohio.

OSWALD SCHLAUPITZ.
